CLAIM

The ornamental design for the stackable computer system, as shown and described.

DESCRIPTION

FIG. 1 is a front elevational view of a stackable computer system showing my new design with broken lines shown for illustrative purposes only and forming no part of the claimed design;

FIG. 2 is an enlarged top plan view thereof;

FIG. 3 is a right side elevational view thereof;

FIG. 4 is a left side elevational view thereof;

FIG. 5 is a back elevational view thereof;

FIG. 6 is an enlarged bottom plan view thereof; and,

FIG. 7 is a perspective view thereof.

FIG. 7

FIG. 2

FIG. 3
